COMBINED CAR WASTEBASKET AND ACCESSORY HOLDER

James C. Fry, Wooster, Ohio, assignor to Rubbermaid
Incorporated, Wooster, Ohio

Filed Dec. 15, 1972, Ser. No. 315,519

Term of patent 14 years

Int. Cl. D12—16; D7—07

U.S. Cl. D87—1 R

FIG. 1

FIG. 3

FIG. 1 is a perspective view of a combined car wastebasket and accessory holder showing my new design.

FIG. 2 is a top plan view thereof.

FIG. 3 is a vertical sectional view on line 3—3 of FIG. 2.

The undisclosed side and end are substantially plain.

I claim:

The ornamental design for a combined car wastebasket and accessory holder, as shown and described.
